CLAIM

The ornamental design for an anti-kink sleeve for garden hose, as shown and described.

DESCRIPTION

FIG. 1 is a perspective view of an anti-kink sleeve for garden hose showing my new design;

FIG. 2 is an enlarged perspective view thereof;

FIG. 3 is a right side elevational view thereof;

FIG. 4 is a left side elevational view thereof;

FIG. 5 is a right end view thereof;

FIG. 6 is a left end view thereof;

FIG. 7 is a top plan view thereof; and,

FIG. 8 is a bottom plan view thereof.

The portions shown in broken lines in FIG. 1 are for information only and form no part of the claimed design.
